Primary Examiner — Steven J Czyz

(57)

CLAIM

The ornamental design for a garment rack, as shown and described.

DESCRIPTION

FIG. 1 is a perspective view of the garment rack showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is another use status perspective view thereof.
The broken lines illustrate portions of the garment rack that form no part of the claimed design.

1 Claim, 8 Drawing Sheets
